UNITED STATES PATENT OFFICE.

GEORGE LYNDEN ROCK, OF CICERO, ILLINOIS, ASSIGNOR TO WESTERN ELECTRIC COMPANY, INCORPORATED, OF NEW YORK, N. Y., A CORPORATION OF NEW YORK.

SPOOL AND METHOD OF MANUFACTURING SPOOLS.

Application filed April 27, 1927. Serial No. 187,001.

This invention relates to spools and a method of manufacturing spools, and more particularly to a spool comprising a drum or core having attached heads and a method of manufacturing such a spool.

This invention is particularly applicable to a spool structure for electro-magnetic coils of the type wherein a tubular frame supporting the coils and composed of fibrous material, such as paper, interconnects a pair of apertured heads disposed at either end thereof and extends into the apertures, the tubular frame containing preferably a laminated core of magnetic material.

15 The objects of this invention are to provide spools of an improved type having attached heads and a method of manufacturing them wherein a strong inexpensive and simple spool structure results.

20 In accordance with the objects of this invention as practiced in connection with the manufacture of spools adaptable for electro-magnetic coils of the type hereinbefore described, the heads upon the tubular fibrous core frame at either end thereof are attached thereto by means of a headed pin inserted in an aperture formed in the head at an angle to and opening into the aperture provided for the tubular frame, with 25 a portion of the wall of each aperture lying tangent to the other, the pin being then driven along the aperture until it becomes wedged between the head and the frame, with one side of the head of the pin embedded in the fibrous tubular frame and the shank of the pin also embedded in the abutting surfaces of the head of the spool and the frame.

Other objects and advantages of this invention will more fully appear from the accompanying detailed description taken in connection with the accompanying drawing which illustrates one embodiment thereof, in which

45 Fig. 1 is a perspective view of a completed spool applicable for supporting electro-magnetic coils and embodying the features of this invention produced by the improved method, showing the tubular frame 50 with a laminated core therein and the two heads, but without any winding, and

55 Fig. 2 is a detail section on the line 2-2 thereof showing the attachment of the heads to the frame.

Referring to the drawing, particularly to

Fig. 1 which illustrates a completed spool for electro-magnetic coils with the coil omitted, a tubular core frame 10 carries a head 11 at either end thereof. The frame 10 is composed of fibrous material, such as paper, its aperture being filled with a plurality of core pieces 12 comprising strips of magnetic material, thus providing a laminated core. The heads 11 are preferably made of fibrous material, such as wood, although any suitable material may be used, and are in the embodiment illustrated shown as being provided with a plurality of flat surfaces 13 to facilitate the mounting of the completed electro-magnetic coil when installed for use. An aperture 14 provided axially in each of the heads 11 receives the opposite ends of the frame 10, the frame at the time of assemblage containing the core pieces 12 which are tightly fitted therein, 70 the ends of the frame being tightly fitted within the apertures and disposed flush with the outer end surfaces of the heads. The improved method of rigidly securing the heads 11 to the frame 10 to positively prevent relative movement between the parts of the spool, whether it be of a rotary or longitudinal movement, comprises the following:

The heads 11 in addition to the axially disposed apertures 14 formed therein for the insertion of the ends of the frame 10 are each provided with an aperture 15 which extends inwardly from one of the flat surfaces thereof and at right angles to the longitudinal axis of the aperture 14, the inner end of the aperture 15 opening into the aperture 14. The aperture 15 is of smaller diameter than the aperture 14 and is disposed at one side of the longitudinal axis of the latter aperture, as clearly shown in Fig. 2, so that a portion of the wall of the aperture lies substantially tangent to a portion of the wall of the aperture 14. After the mounting of the heads 11 upon the opposite ends of the frame 10, a headed pin or brad 16 with a pointed end is inserted into each of the apertures 15, head up. It will be apparent that the pointed end of the pin 16 upon being positioned in the aperture 15 will engage the curved outer surface of the frame 10 and be directed toward the portion of the wall of the aperture 15 that lies tangent to the aperture 14 or to the peripheral surface of 110

the frame 10 when assembled with the heads 11, and thereafter upon being driven in or staked that it will become firmly wedged between the tangentially disposed portion of 5 the wall of the aperture 15 and the peripheral surface of the frame 10. The pin 16 is driven in until a portion of the peripheral edge of its head, as clearly indicated in Fig. 2, is forced into or embedded in the 10 fibrous composition of the frame 10 and the wedging action of the shank of the pin is such that it is forced into or embedded in the material composing the head 11, in the present instance wood, and the fibrous frame disposed at opposite ends thereof.

It will be apparent that the method as 20 herein described of attaching the spool heads 11 to the core from 10 provides a rigid spool structure wherein relative movement between the respective parts thereof is greatly minimized and one in which no adhesive is used, thereby eliminating all tendency of corrosion occurring upon the wire comprising the coils and the laminated core, 25 which might result from moisture contained in liquid adhesive.

Although the invention as herein illustrated and described is particularly well 30 adapted for use in connection with spool structures for supporting electro-magnetic coils, it should be understood that the novel features thereof are capable of use in spool structures for other purposes and should be 35 limited only by the scope of the appended claims.

What is claimed is:

1. The method of manufacturing spools having attached heads, which consists in forming an aperture in a head for the insertion of a core, forming a second aperture in the head at an angle to the longitudinal axis of the first aperture and extending only to the periphery of the first aperture and at one point thereof, inserting the core in the first aperture, inserting a member 40 in the second aperture, and then causing the member to be driven in a direction at an angle to the longitudinal axis of the second aperture until it is wedged between abutting surfaces to thereby rigidly unite the 45 head and the core.

2. A spool comprising a core, a head provided with an aperture for receiving the core and a second aperture disposed at an angle to the longitudinal axis of the first 50 aperture and extending only to the periphery of the first aperture and at one point thereof, a portion of the wall of the second aperture lying tangent to a portion of the wall of the first aperture, and a pin of less 55 diameter than that of the second aperture into which it is entered, positioned between abutting surfaces of the core and the head at the periphery of the core, and thereby rigidly uniting the head and the core and 60 at an angle to the longitudinal axis of the second aperture.

In witness whereof, I hereunto subscribe by name this 14 day of April, A. D. 1927.

GEORGE LYNDEN ROCK.
